INCLINED PILLOW REST FOR BEDS AND COUCHES

Diana P. Williams, Boston, Mass.

Application September 2, 1932, Serial No. 631,518

2 Claims. (Cl. 5—327)

My invention aims to produce a novel and improved inclined pillow rest for use by invalids and others in connection with beds and couches which will better remain in position when once adjusted in place of the adjustable inclined frames now commonly used in connection with the ordinary rectangular pillows or in lieu of the use of loose pillows as they are now used.

My invention will be best understood from a description of the preferred embodiment thereof illustrated in the accompanying drawing.

Referring to the drawing,

Figure 1 is an edge view of a pillow rest made in accordance with my invention;

15 Fig. 2, a rear or right hand elevation of the pillow shown in Fig. 1;

Fig. 3, a perspective view showing my improved pillow with a suitable case or slip applied thereto as when commonly in use;

20 Fig. 4, a side view showing a section of the head portion of a bedstead with my improved pillow secured in position thereon; and

Fig. 5, an enlarged detail of the supporting seam to be referred to.

25 Referring to the drawing and to the particular embodiment of my invention selected for illustration herein, my improved pillow in either front or back view, the latter of which is shown in Fig. 2, is of suitable shape, but preferably

30 broad and generally rectangular with a straight horizontal bottom edge 1, vertical side or end edges 2, and a preferably arched top edge 3. The front face of my improved pillow, Fig. 1, is made crowning from edge to edge as indicated at 4, to provide for usual contained upholstering and forming a front section 44, which is convex, Fig. 1, while the back face, Fig. 1, 5 is made similarly crowning for upholstery, down to a point approaching, but some distance removed from

40 the bottom edge of the pillow, where it terminates at 6 in a slightly arched and generally horizontal edge forming a rear upper section 55, which is convex and upwardly tapering and which extends from side to side of the pillow and

45 is secured to the latter by and along the end seams 7 which follow generally the outline of the pillow.

Between the arched edge 6 and the bottom edge 1 of the pillow at the rear side thereof is 50 inserted a horizontal, in cross section triangular, base piece 8, secured by the edge stitching along the bottom edge 1 of the pillow and up the side edges thereof to the point where it meets the edge 6 of the upper part forming a lower 55 rear section 88 triangular in cross section. The

upper edge of the base piece 88 and the bottom edge 6 of the upper portion 55, at the rear of the pillow, are united across the pillow and preferably in a generally arched line, by a line of stitches 9 extended through the infolded adjacent edges of said base section 88 and rear piece section 55, to form a stiff supporting seam, as clearly shown in Fig. 5. In lieu of stitches, any other preferred form of fastening means or devices may be employed.

60 The dimensions of the parts are such that the pillow formed as described presents at its front face 4 a pillow support of generally conventional shape and so also at the rear upper portion 5 at the rear face 5, but at the bottom 65 of the rear face the base piece 88 presents rather an abrupt inclined or oblique support outlined and stiffened at its upper and lower edges 6 and 1 by the seams employed to secure together the parts of the pillow, which inclined base serves 70 naturally and securely to support the pillow when in use in an inclined position such as shown in Fig. 4, from which it will not readily become displaced when in use.

75 The line of stitches 9, Fig. 4, at the seam 6 tends naturally to provide a fullness or thickened portion of the pillow in the vicinity of said seam, which tends further to give stability and support to the pillow when in use.

An enclosing slip is preferably employed in 80 connection with and as a part of my pillow, as shown in Figs. 3 and 4, the same being cut generally to the shape of the pillow proper and seamed together around the side and top margins 10 and 11, and along the line of the supporting seam 6 by a similar seam 12 with its bottom edges 13 closed together by stitches for a short distance inwardly as at 14, 14, near each side, and left open between said closed edge portions to permit placing of the pillow proper 90 within and withdrawing it conveniently from the pillow slip. Preferably the dimension of the casing or slip from the top to bottom will exceed by a few inches that of the corresponding dimension of the pillow to provide a flap like bottom to the case which may be infolded one or more times beneath the base of the pillow to retain the latter in position when in use, and said prolonged bottom edge prior to infolding may be secured at one or more points by tapes 15 100 that may be tied together.

105 While the tendency of the pillow, by reason of the oblique base and triangular section 88 at the rear side, is to retain itself naturally and normally in an inclined position as shown in Fig. 110

4, to guard against accidental displacement, the pillow case may be provided at its rear face and preferably somewhere about the middle with securing tapes 16 which may be tied around the 5 ordinary rods or pilasters of the head of the bedstead, as indicated in Fig. 4.

The flexibility and conformable nature of the pillow and its contents are such that the same, due to its oblique base section 88, may be placed 10 in positions of different inclination and adapt itself thereto and remain naturally therein without any of the mechanical means utilized in the pillow rests of the conventional type now in use, so that in effect my oblique base pillow has all 15 the adjustability of an adjustable one such as referred to without any of the machinery, weight, inconvenience, or hardness of a mechanical rest. I provide a pillow that, when in position, will stay there partly because of the large flat base 20 provided by the lower section 88 of the case and triangular supporting upper rear section 55 which form with each other a wedge support behind and beneath the front section.

My invention is not limited to the particular 25 illustrated embodiment herein disclosed.

I claim:

1. A pillow comprising a case filled with suitable material and having clearly defined outlining edges, upholstered more deeply at the front 30 side of the vertical end edges than the other, to form a convex front and a convex rear section of the pillow, the bottom of the upper rear sec-

tion being more deeply upholstered than the top portion thereof, and a longitudinal seam at the bottom of the rear upper section slightly convex relatively to the bottom edge to define a secondary edge and forming, with the bottom edge, end edges of the case and a rear section wall, a horizontal triangular cross-sectional base case-section with a flat base line and curved end lines and adjacent upright triangular case section with a curved base line and substantially flat end lines, the whole forming a pillow with a generally triangular end with a flat base edge and top converging front and rear lines.

2. A pillow comprising a case filled with suitable material and having clearly defined outlining edges, upholstered more deeply at the rear of the vertical end edges than the front, to form a front and a rear section of the pillow, the bottom of the upper rear section being more deeply upholstered than the upper portion thereof, and a longitudinal seam in the rear section slightly convex relatively to the bottom edge to define a secondary edge and forming, with the bottom edge, and end edges of the case and rear section end wall, a pillow having a front case-section supported in an inclined position by a lower horizontal base section substantially triangular in cross section with a flat base curved upwardly at its ends, and an upright rear upper section with a slightly curved base and substantially straight end edges.
